UNITED STATES PATENT OFFICE

RUDOLPH W. BUETTNER, HELMER E. ERICKSON, AND HENRY H. TALBOYS, OF MILWAUKEE, WISCONSIN, ASSIGNORS TO NORDBERG MANUFACTURING CO., OF MILWAUKEE, WISCONSIN, A CORPORATION OF WISCONSIN

ADZING MACHINE

Application filed February 7, 1929. Serial No. 338,066.

Our invention relates to a machine or power plant adapted for use upon railroad tracks and particularly adaptable, for example, for adzing off ties to even them to receive rails to be laid upon ties or to be relaid upon ties which have already been used. One object of our invention is the provision of such a device which may ride upon and be conveyed along railroad tracks where two rails are in place, and which, at time of use, may be supported upon a single rail. Another general object of our invention is to provide a traveling power plant which may be employed for work to be done on railroad ties, track, roadbed or the like. Another object is the provision of a device in which a track or tie engaging member may be normally held by gravity out of contact with the work, but which may be thrust by the operator against the work. Other objects will appear from time to time in the course of the specification and claims.

We illustrate our invention more or less diagrammatically in the accompanying drawings, wherein—

Figure 1 illustrates a plan view;

Figure 2 illustrates a side elevation of the device when in use;

Figure 3 is a side elevation of the device when in condition for transportation;

Figure 4 is a section on the line 4—4 of Figure 3;

Figure 5 is a detail front elevation of the handle and guard plate;

Figures 6, 7 and 8 show the cutter end of three variant forms, and

Figure 9 is a detail section.

Like parts are indicated by like symbols throughout the specification and drawings.

Referring, for example, to Figures 1, 2 and 3, the parallel longitudinal frame elements A¹ have suitable transverse or end connecting members A². A⁴ A⁴ are rail contacting flanged wheels journaled, for example, in the bearings A⁵ on the members A¹.

B B indicate transverse frame members which rest upon and are secured to the longitudinal members A¹ in any suitable manner. The members B at one end are connected by a transverse frame member B¹, and at their opposite end are connected for ex-

ample by the short transverse member B². The ends B³ of the members B have bolted between them a bearing block or casting which will later be discussed in greater detail.

Mounted on the end of the members B adjacent the transverse member B¹ is any suitable engine supporting frame or plate indicated as C in Figures 1 and 2. This plate is illustrated as adjustable along the members B as by the adjusting slots C¹ shown in Figure 1. The bolts C² pass therethrough and any suitable locking members may be used to lock the plate in adjusted position, for example the nuts C³. C⁴ generally indicates any suitable power source, herein indicated as an internal combustion motor. It will be realized that any suitable operating means or drive or connection may be employed to provide power for the driving of the parts later described. However, we illustrate in connection with the engine C⁴ a pulley C⁵ adapted to drive the drive belt C⁶. C⁷ C⁷ indicate angle members extending across the members A¹. Upon them are mounted vertical supports C⁸ provided with a plurality of apertures C⁹ through any of which may pass a shaft C¹⁰ upon which is rotatably mounted the belt guiding pulley C¹¹. The purpose of the guiding pulley C¹¹ is to guide the belt C⁶, which passes about the horizontal pulley C⁵ and the vertical pulley H⁷. Whereas we have shown practical belt guiding means, it will be understood that we do not wish to be limited to the specific details herein described and shown, except so far as limited by the actual language of our claims.

Referring primarily to Figures 1 and 3, when the device is in position to be transported along a track in which both rails are in position, the wheels A⁴ engage one rail of the track and a wheel D engages the opposite track. This wheel D is mounted at the end of any suitable support, for example the angle iron D¹, which is pivoted as at D², intermediate the ends of one of the transverse frame members B. It may be pivoted, for example, in a yoke D³, which yoke in turn is pivoted as by the bolt D⁴, to provide what is in a broad sense a universal joint or connection between the end of the member D¹ 100

and the frame member B to which it is secured. D⁵ indicates a transverse extension from the member D¹ which extension, when the members D D¹ are in the dotted line position of Figure 1 or in the position in which they are shown in Figure 3, abuts against the transverse frame member B². We may provide any suitable means for securing D⁵ in relation to B², as for example by the bolt 10 D⁶ upon which is rotatably mounted the nut D⁷ with its handle D⁸ which serves to make its manual rotation easy and to lock it and keep nut D⁷ from turning off by vibration. When the wheel D and its supporting member are in the dotted line position of Figure 1 or in their full line position of Figure 3, the entire device may be moved along the track either manually or by any suitable coupler connection to a hand car or the like. 15 20 When the wheel D is in contact with the rail, the cutting or operating mechanism below described is held out of contact with the track, ties and roadbed.

When it is desired to use the device, for example to adze off a tie, the wheel D and its support D¹ may be rotated into the full line position of Figures 1 and 2, at which time the member D¹, as shown in Figure 2, rests upon the top of the nearest longitudinal support 25 A¹, and the wheel D, which may be made considerably heavier than the usual railroad wheel, serves as a counterweight to tilt the frame members B³, and the devices carried thereby, upwardly from track, ties and roadbed. The wheels A⁴ maintain their contact 30 with the rail, and the device may thus be rolled along a single rail, as when the other rail has been removed. In order to limit this upward tilt in response to the counterweight, 35 we may provide any suitable abutment for the opposite ends of the frame members B. As shown in Figures 2 and 3 we may employ, for example, a shoe or roadbed contacting member E, with the eye E¹, mounted 40 in any suitable bearing block E². E³ is a take-up nut engaging the ends of the oppositely threaded bolts E⁴ E⁵ whereby rotation 45 of the nut E³ lengthens or shortens the total length of the device. The device when not 50 in use may be hooked up by any suitable hook or support E⁶, as shown in Figure 3. It will be realized that we do not wish to be limited to any specific supporting means but that we 55 find it desirable to provide some abutment, preferably adjustable, whereby when the wheel D is serving as a counterweight the upward lifting of the frame members B may be limited to some predetermined level. The member E is preferably upturned or beveled 60 at the ends to permit it to ride along the ties.

When the device is in working position to adze ties and supported only upon the wheels A⁴, means are necessary for holding said wheels upon the rails. As an example 65 of such means we may form the end plates

A² as shown in Figure 2 to include a pair of adjacent arcuate portions G G¹. To each such portion is pivoted, as at G² G³, roller supporting arms G⁴ G⁵ with the rollers G⁶ G⁷ at the ends thereof, each such roller being adapted to engage an opposed face of the side of the rail. The edges of the arcuate portions G G¹ are formed with a plurality of adjustment apertures G⁸ which may be penetrated for example by securing pins or bolts 70 G⁹ on the arms G⁴ G⁵. We may therefore adjust the rollers G⁶ G⁷ to center the cutting or working head H⁸ directly over the center of the groove made by the other rail in the old ties to be adzed or slightly off center as desired. The broad tread of wheels A⁴ allows quite an adjustment before it is necessary to move wheels A⁴ either way on their journal or axle which is carried in bearings A⁵ A⁵. As the machine is moved forth and 80 back across the tie to be adzed it can be moved more easily with roller guides to keep it on the rail than when depending on the flanges of wheels A⁴ A⁴ for one side and a roller on the other side of the rail. The rollers cause 85 less friction than the flange of the wheel. In practice a measure of play is necessary in order that the rollers may not bind when the device is tilted.

Under some circumstances it may be possible to dispense with the rollers G⁶, leaving only the rollers G⁷ which are opposed to the flanges of the wheels A⁴. 90

Figure 2, and the full line structure of Figure 1, indicate the device in operating position. Referring for example to Figure 2, we may employ an operating or working structure which includes the bearing member generally indicated as H. It includes the bearing sleeve H¹, which may have cast 100 or secured to it webs H² and a block H³ which may be secured between or bolted between the ends of the frame members B³. In order to provide a measure of adjustment for such block we have illustrated the inclined apertures B⁴ in the frame members B³ through which may pass the securing bolts H⁴ which receive the securing nuts H⁵. 110

Mounted for rotation within the bearing sleeve H¹ is any suitable rotatable and preferably hollow shaft H⁶, to the upper end of which is secured a pulley H⁷ about which passes the belt C⁸. At the lower end of the shaft H⁶ is any suitable working head H⁸, upon which are mounted any suitable working members or cutters generally indicated as H⁹. 115

Whereas we have illustrated our device as having a generally vertical cutting shaft with cutters at the lower end thereof, such shaft being driven by a pulley, it will be realized that we do not wish to limit ourselves to any such specific driving or cutting means. We may employ other cutting arrangements and other driving means. We illustrate for 120 125 130

example in Figure 6 a block I, adjustable on the ends of the members B with a shaft I¹ therewithin, such shaft having the pulley I² at the top thereof and a bevel gear I³ at the bottom.

Such gear meshes with an opposed bevel gear I⁴ on the horizontal shaft I⁵, such shaft having cylindrical cutters I⁶ at each end thereof. I⁷ indicates any suitable stop projection on the member I whereby the downward movement of the cutters may be limited in their operation upon a railroad tie, when the cutters I⁶ have reached the level of the bottom of the already formed track groove.

In Figure 7 we illustrate a form of cutter similar to that shown in Figure 6, such cutter or pair of cutters, however, being driven by a flexible shaft I⁸.

Figure 8 indicates a further variation of our device in which a drive shaft K acting through any suitable joint K¹ rotates the sprocket K² which, through any suitable chain or belt K³, drives the sprocket K⁴ upon the shaft K⁵ and thereby rotates the cutters I⁶.

It will therefore be realized that although we have described and shown a practical and operative device, nevertheless we wish our drawings and description to be taken as in a broad sense illustrative and diagrammatic, rather than as tying us precisely and particularly to the structure shown, except so far as we limit ourselves by our claims. Thus we may employ cutters rotatable about a horizontal axis or about a vertical axis or any other suitable axis, and we may employ flexible drives and drive shafts or driving pulleys, without departing from the spirit of our present invention.

In operation the engine preferably idles when not in use. A handle may be provided, shown for example in Figures 2 and 5 as including the cross-piece L, whereby the user may thrust the cutter against the gravitational effect of the counterweight wheel, in order to operate on the tie. L¹ are hand pieces on such cross-piece. We may employ any suitable means, for example a flexible connection between the handle L and the engine, whereby the operator, either automatically or at will, opens the throttle when he grasps the handle, and runs the engine at full speed. The handle L is supported on the two bars L², which are secured to the forward ends of the frame members B³, as by welding. A guard or shield L³ is flexibly supported as by the chains L⁴. Second chains L⁵ limit the approach of the guard to the cutter. A similar guard L⁶ may be mounted at the opposite side of the cutter, supported as by the chains L⁷ and its approach to the cutter limited as by the chains L⁸.

The guards L³ and L⁶ are positioned in the lateral plane of discharge of chips, shavings and the like from the rotary cutters of the

working head. The operator stands to the left of the cutting head, taking the parts in their position as shown in Figure 2, and were a guard not provided the rotation of the cutting head would throw out chips laterally in all directions. The guard L³ prevents their discharge against the feet or legs of the operator. The guard L⁶ prevents their discharge toward the engine.

The fact that some roads incline the rails towards the center, and also the necessity for banking the cuts on a curve, makes the adjustment of the angle of the cutter head, for example in the slots B⁴, of considerable importance.

M is a cord extending from a lever M¹, on one of the handle grips L², whereby the speed of the engine may be controlled. It will be understood that the cord extends from any suitable throttle mechanism the details of which form no part of the present invention and are therefore not indicated herein.

Whereas we have illustrated this device in connection with means for adzing off rails, it may be obvious that it can be employed as a power plant for driving other mechanisms. For instance, by substituting other tools we may employ the device for drilling, pulling and driving spikes, turning up bolts, etc., in which case it may take the place of an air drill. Whereas we have not illustrated any specific coupling, it will be realized that a coupling device may be employed whereby the device may be pulled by a motor or hand car. Whereas the device is particularly adaptable to adzing old ties, it will also surface a new tie to conform to the central plane of the cutter.

The use and operation of our invention are as follows:

Our device is shown as applied to the adzing of the top surfaces of ties to receive the rails of a railway track. We wish it understood, however, that, although this is a preferred use of our device, our invention is applicable, also, for other purposes, and, in fact, may be employed for practically any operation in which a tool has to be used upon or directed against a railway tie or a rail, or any other object within reach of the rail upon which the device is mounted.

However, considering the application of our invention to an adzing machine, we illustrate a frame long enough to extend across both rails of the usual railway track. Mounted upon this frame is a working head, the head shown being particularly adaptable for adzing of the top of a tie. Assuming that this head is to work upon the top of a tie at a point from which the rail has been removed, we provide means, viz: the wheel D, which has the multiple function of aiding in the support of the device when it is conveyed along a railway track, and of holding the cutter head out of contact with the rail when

the device is being so conveyed, and of acting as a counterweight to tilt the frame upwardly away from the tie, when it is moved to the dotted line position in which it is shown in Figure 1. In the form of the device herein shown we illustrate as power plant an internal combustion engine. This engine is placed adjacent the rail engaged by the wheels A⁴, viz: the wheels which are in constant engagement with a rail. The wheel D is preferably of such weight as to hold the end of the frame down in the position in which it is shown in Figure 3. When it is swung to its opposite position, the full line position of Figure 1, it co-operates with the weight of the engine in tilting the opposite end of the frame upwardly into inoperative position. When it is so tilted the operator can thrust the cutter head downwardly against the rail; the parts and weights being so proportioned that an operator can easily thrust the cutter head downwardly, although when his manual thrust is released the weight of the counterweight, or of the counterweight and engine, immediately rotates the cutter head upwardly away from the tie.

In a device of this type, in which during operation the frame is mounted on a single rail, it is necessary to provide means for holding the wheels A⁴ in position on the rail.

As an example of such means we illustrate the rail engaging rollers G⁶ G⁷, which are shown, as in Figure 3, adjustable toward and away from the rail. It is important that there should be such adjustment, since the size, height and width of rail may vary and the cutters H⁹ need be adjusted. An increase in the height of the rail affects the angular relation of the cutting plane to the tie. Any adjustment necessary to care for height or width of rail and location or inclination of the cutting plane may be effected by the adjustment of the rollers G⁶ and G⁷, together with the adjustment of the axis of the cutter in relation to the frame B or, more properly stated, in relation to the plane of the tie. A further adjustment is effected by the lateral movement of the wheels A⁴ in the bearings A⁵, as shown in detail in Figure 9, in which, for example, we illustrate the apertures A²⁰ in the shafts A²¹ and the cotters or pins A²² passing therethrough, the wheels A⁴ being pinned or secured to the shafts A²¹.

In order to limit the gravitational tilting movement, we may provide any suitable ground or tie engaging member, for example the contacting member E, the ends of which may be rounded or upwardly beveled, to permit it to slide along the roadbed and ties as the device is shifted.

In order to maintain the necessary adjustment of drive motor means and the like, we mount the engine upon a plate which is adjustable on the frame. The cutter head is adjustable, as in the slots B⁴. The slots B⁴

are preferably concentric, being described about a center lying on the axis of rotation of the cutter head and adjacent the bottom of the stop H¹⁰. The belt guiding pulley or roller C¹¹ is also indicated as adjustable. The object of this pulley is to guide the belt from the vertical belt pulley C⁵ to the horizontal belt pulley H⁷, as shown, for example, in Figure 3. In changing the angle of the cutter head spindle as shown in Figure 3, as by adjusting it in the slots B⁴, the distance separating the pulley H⁷ and the pulley C⁵ is varied greatly, as the relation of the cutter spindle to the slots B⁴ is such that the adjustment is effective as if the upper end of the cutter spindle were rotated about the center of the bottom or stop H¹⁰. It is therefore necessary to adjust the pulley C¹¹, which adjustment may be effected by means of the aperture C⁹ through which the shaft C¹⁰ may be passed. This adjustment may be made effective to hold or guide the belt C⁶.

Whereas we have shown in a number of the drawings a belt drive, it will be realized that we do not wish to be limited specifically thereto except as set out in the claims. Thus in Figure 7 we illustrate a flexible drive and in Figure 8 a driven shaft K which, through a sprocket K², drives the chain K³ and the sprocket K⁴.

In order to permit the operator to thrust the tool or cutter head downwardly against the tie, we illustrate a cross-piece L with the hand engaging members L¹, the side bars L² extending downwardly to and being connected to the frame elements B. L³ is a guard or shield flexibly supported by the members L⁴, L⁵. This shield L³ extends downwardly approximately to the road-bed level when the tool is in operative position and tends to protect the feet of the operator from contact with the cutting head and from material cut from the tie, which might otherwise be projected outwardly against the operator.

We prefer in normal operation to permit the engine C⁴ to idle, it being speeded up only when the cutter head is actually in engagement with the work. We may employ, for example, the flexible connection, wire or rope or the like, indicated in Figure 2 as M, which extends to a lever M¹ associated with one of the hand pieces L¹, which may be made rotatable upon the cross-bar L. As the operator thrusts downwardly upon the handles L¹ he may at the same time tighten the control part M and thereby accelerate the motor.

In a number of the claims we describe the transverse connection between the two rails, or the member on which the cutter is mounted, as a frame. It will be understood that we wish the word "frame" to be interpreted sufficiently broadly to cover any extension or member upon which the cutter is mounted. Preferably several channel or angle irons will

be used but a single channel or angle member, if of proper strength and cross-section, might be employed.

Where in the claims we employ the word "track" or "railroad track" we wish this term 5 to be interpreted with sufficient breadth to cover a railroad track taken generally, including the rails, ties and adjacent road bed. Thus where we speak of a machine operative upon a track or having parts movable 10 downwardly toward or upwardly away from the track we wish it to be understood that the machine may be employed to operate upon the rails or the ties or the road bed. The 15 particular type of machine herein disclosed is primarily designed for operating upon the ties, but a mere change in the working head will adapt it for other purposes.

We claim:

1. In a machine adapted for use upon a railroad track, supporting wheels adapted to engage one rail, a frame mounted upon said supporting wheels, a working member mounted on said frame and means for actuating it, a track engaging member, associated with said frame, shiftable from one position in which it engages an opposite rail, to another position in which it tilts said frame and head, upwardly away from the work.

2. In a machine adapted for use upon a railroad track, supporting wheels adapted to engage one rail, a frame mounted upon said supporting wheels, a working member mounted on said frame and means for actuating it, a track engaging member, associated with said frame, shiftable from one position in which it engages an opposite rail, to another position, in which it tilts said frame and member upwardly away from the work, and a supporting member for said track engaging member, said supporting member being pivotally secured to said frame.

3. In combination with a machine adapted for use upon a railroad track, a frame spanning the rails of said track, a wheel movably mounted upon said frame adapted when in one position to engage a rail of said track, and to assist in the support of said frame, and adapted when in another position to serve as a counterweight for tilting said frame.

4. In a machine adapted for use upon a railroad track, track engaging supporting means adapted to engage one rail of said track, a frame associated with said supporting means and tiltable in relation to said rail, a working member mounted on said frame and means for actuating it, an additional rail engaging member, associated with said frame, and adapted to engage the opposite rail of the track and adapted to be moved into and out of rail engaging position, and adapted, when in one position, to serve as a counterweight to tilt the frame and working member into inoperative position.

5. In a machine adapted for use upon a

railroad track, supporting means adapted to engage one rail, a frame mounted upon said supporting means, a working member upon said frame, power means upon said frame and a driving connection between said power means and said working member, means for normally tilting said frame and working member out of operative position by substantially balancing them on said rails, and means for limiting the extent of said tilting movement, including a ground engaging member adapted to be moved into contact with the ground in response to tilting movement of the frame.

6. In a machine adapted for use upon a railroad track, supporting means for said machine adapted to engage a single rail only of said track, a member, mounted upon said supporting means and extending laterally from the rail and supporting means, means for substantially balancing it upon said single rail during the actual operation of the machine, and a working head mounted adjacent the end of said laterally extending member opposite to the rail upon which the member is supported.

7. In a machine adapted for use upon a railroad track, supporting means for said machine adapted to engage a single rail only of said track, a member, mounted upon said supporting means and extending laterally from the rail and supporting means, adapted to be supported solely upon said single rail during the actual operation of the machine, and a working head mounted adjacent the end of said laterally extending member opposite to the rail upon which the member is supported, said laterally extending member being tiltably supported upon said rail, and means for maintaining it with its outer end, together with the working head, normally tilted upwardly away from the track, when the machine is ready for actual operation, the laterally extending member being tiltably downward for working contact of the working head and track.

8. In a machine adapted for use upon a railroad track, supporting means for said machine adapted to engage a single rail only of said track, a member, mounted upon said supporting means and extending laterally from the rail and supporting means, adapted to be supported solely upon said single rail during the actual operation of the machine, and a working head mounted adjacent the end of said laterally extending member opposite to the rail upon which the member is supported, said laterally extending member being tiltably supported upon said rail, and means for maintaining it with its outer end, together with the working head, normally tilted upwardly away from the track, the laterally extending member being tiltably downward for working contact of the working head and track, and means for adjusting the

position of the working head in relation to the laterally extending member.

9. In a machine adapted for use upon a railroad track, a transverse frame adapted to span the rails of said track, supporting means for said frame adapted to engage one rail only of said track, said frame being substantially balanced upon said single rail for tilting movement downwardly toward and upwardly away from portions of the track laterally spaced from said rail.

10. In a machine adapted for use upon a railroad track, a transverse frame adapted to span the rails of said track, supporting means for said frame adapted to engage one rail only of said track, said frame being tiltably supported upon said single rail for tilting movement downwardly toward and upwardly away from portions of the track laterally spaced from said rail, and an additional supporting member movably associated with said frame, adapted when in one position to engage the opposite rail of said track and adapted when in another position to serve as a counterweight for tilting the frame upwardly away from laterally spaced portions of the track.

11. In a machine adapted for use upon a railroad track, a transverse frame adapted to span the rails of said track, supporting means for said frame adapted to engage one rail only of said track, said frame being substantially balanced upon said single rail for tilting movement downwardly toward and upwardly away from portions of the track laterally spaced from said rail, a working head rotatably mounted upon a portion of the frame remote from said single rail, and actuating means for said working head positioned on a portion of the frame adjacent said single rail.

12. In a machine adapted for use upon a railroad track, a transverse frame adapted to span the rails of said track, said frame being mounted upon and supported upon one rail only of said track, when the machine is in position for use, said machine including a working head and gravitational means for holding said head normally withdrawn upwardly from the track prior to the initiation of working contact with the track, said head being adapted to be manually thrust downwardly into contact with the work.

13. In a machine adapted for use upon a railroad track, a transverse frame adapted to span the rails of said track, supporting means for said frame adapted to engage one rail only of said track, said frame being tiltably supported and substantially balanced upon said single rail for tilting movement downwardly toward and upwardly away from portions of the track laterally spaced from said rail, a working head rotatably mounted upon a portion of the frame remote from said single rail, and actuating means

for said working head positioned on the opposite side of said single rail from the working head.

14. In a machine adapted for use upon a railroad track, track engaging supporting wheels adapted to engage one rail only of a track, a frame mounted upon said wheels and substantially balanced upon said single rail, a working member mounted on said frame and means for actuating it, and a wheel movably mounted upon said frame, said wheel being shiftable from one position in which it engages an opposite rail to another position in which it is out of contact with said rail.

15. In a machine adapted for use upon a railroad track, track engaging supporting wheels normally engaging one rail only of a track, a frame mounted upon said wheels and substantially balanced upon said single track, said frame extending laterally from said rail for a distance as great as the normal width of a track, a working member mounted upon said frame and means for actuating it, and means for tilting said frame as a whole, and for tilting the working member upwardly away from the track about an axis conforming generally with the location of the rail upon which the frame is balanced.

16. In a machine adapted for use upon a railroad track, track engaging supporting wheels normally engaging one rail only of a track, a frame mounted upon said wheels and substantially balanced upon said single track, said frame extending laterally from said rail for a distance as great as the normal width of a track, a working member mounted upon said frame and means for actuating it, and means for tilting said frame as a whole, and for tilting the working member upwardly away from the track about an axis conforming generally with the location of the rail upon which the frame is balanced, said means including a counter-weight movably associated with the frame.

17. The structure of claim 16, characterized by the employment of means for limiting the upward tilting movement of the frame and working member.

18. In a machine adapted for use upon a railroad track, supporting means adapted to engage one rail of said track, a laterally extending frame of a length as great as the width of the track, mounted upon said supporting members, and tiltably supported and substantially balanced upon said rail, a working member upon said frame and means for actuating it, said supporting means being laterally adjustable in relation to said frame.

19. In a machine adapted for use upon a railroad track, supporting wheels adapted to engage one rail of said track, a laterally extending frame of a length as great as the width of the track, mounted upon said supporting wheels, and tiltably supported and

substantially balanced upon said rail, a working member upon said frame and means for actuating it, said supporting wheels being laterally adjustable in relation to said frame.

5 20. In a machine adapted for use upon a railroad track, supporting means for said machine adapted to engage a single rail only of said track, means for limiting transverse movement of said supporting means in relation to said rail, a member, mounted upon said supporting means and extending laterally from the rail and supporting means, means for substantially balancing it upon said single rail during the actual operation 10 of the machine, and a working head mounted adjacent the end of said laterally extending member opposite to the rail upon which the member is supported.

21. In a machine adapted for use upon a railroad track, supporting wheels for said machine adapted to engage a single rail only of said track, said wheels including flanges adapted to engage one side of said rail, and means for preventing transverse movement 25 of said wheels in relation to said rail, opposed to the side of the rail opposite to the flanges of the wheels, a member, mounted upon said supporting means and extending laterally from the rail and supporting means, means 30 for substantially balancing it upon said single rail during the actual operation of the machine, and a working head mounted adjacent the end of said laterally extending member opposite to the rail upon which the member is 35 supported.

22. The structure of claim 21 characterized by the employment of a sector plate, a guide wheel support adjustably mounted upon said plate and a guide wheel positioned 40 upon said support and opposed to a side of the rail.

23. In a machine adapted for use upon a railroad track, supporting means for said machine adapted to engage a single rail only of said track, a member, mounted upon said supporting means and extending laterally from the rail and supporting means, adapted to be supported solely upon said single rail during the actual operation of the machine, and a 45 working head mounted adjacent the end of said laterally extending member opposite to the rail upon which the member is supported, said laterally extending member being tiltably supported upon said rail, and means for 50 maintaining it with its outer end, together with the working head, normally tilted upwardly away from the track, when the machine is ready for actual operation, the laterally extending member being tiltable downward for working contact of the working head 55 and track, and means for limiting the tilting movement of said laterally extending member upwardly from the track.

24. The structure of claim 23 characterized 60 by the employment of a ground engaging stop

member associated with the laterally extending member and positioned on the side of the rail opposite to the working head.
